CLAIM

We claim the ornamental design for vehicle recovery track, as shown and described.

DESCRIPTION

FIG. 1 is a front elevational view of a vehicle recovery track; FIG. 2 is a rear elevational view of the vehicle recovery track; FIG. 3 is a right side elevational view of the vehicle recovery track;

FIG. 4 is a left side elevational view of the vehicle recovery track;

FIG. 5 is a bottom plan view of the vehicle recovery track; FIG. 6 is a top plan view of the vehicle recovery track;

FIG. 7 is a bottom isometric view of the vehicle recovery track; and,

FIG. 8 is a top isometric view of the vehicle recovery track.
